UNITED STATES PATENT OFFICE.

TEOFIL GRZYWIENSKI, OF PENFIELD, PENNSYLVANIA.

WINDOW-SCREEN.

1,117,838.

Specification of Letters Patent. Patented Nov. 17, 1914.

Application filed October 11, 1912. Serial No. 725,146.

To all whom it may concern:

Be it known that I, TEOFIL GRZYWIENSKI, a subject of the Czar of Russia, residing at Penfield, in the county of Clearfield, and State of Pennsylvania, have invented certain new and useful Improvements in Window-Screens, of which the following is a specification, reference being had therein to the accompanying drawing.

10 This invention relates to window screens, and the object of my invention is to locate a spring roller in the sill of a window frame and attach to said roller and wind thereon a flexible interwoven wire screen that is also attached to the lower rail of one of the window sashes, whereby when the sash is raised the screen is pulled into position to screen the window and prevent flies or other insects from entering a compartment in connection with which the screen is used. I attain the above object by a mechanical construction that is simple, inexpensive to manufacture, durable, and easily embodied as part of the window frame when said frame is constructed.

25 My invention will be hereinafter specifically described and then claimed, and reference will now be had to the drawing wherein:

30 Figure 1 is a front elevation of a window frame in accordance with this invention, Fig. 2 is a vertical sectional view of the same, and Fig. 3 is an enlarged detail sectional view of a portion of a window sash, showing the manner of attaching the screen thereto.

To put my invention into practice, I provide the sill 1 of a window frame 2 with a longitudinal slot 3. Secured to the bottom 40 of the sill 1, beneath the slot 3 is a longitudinal housing 4 and located in said housing is a spring roller 5 of the ordinary and well known curtain-shade type, this roller, other than its specific use forming no part 45 of this invention.

Attached to and wound upon the roller 5 is a screen 6 preferably made of interwoven wire, said screen extending through

the slot 3 and having the upper edge thereof clamped between longitudinal parallel 50 flanges 7 of a hold fast plate 8 secured by screws 9 or other fastening means to the bottom rail 10 of a sash 11. The plate 8 is made of a single piece of material doubled upon itself with the longitudinal edges of 55 the plate bent to provide the flanges 7 and these flanges are connected together by rivets 12 or other fastening means that firmly hold the upper edge of the screen 6 between said flanges. The flanges 7 enter 60 the slot 3 when the sash 11 is lowered; the screen 6 being wound upon the roller, which is invisible and does not mar the general appearance of the window. When the sash 11 is raised, the screen 6 is immediately shifted 65 into position to prevent flies and other insects from passing through the open window.

What I claim is:

In a window screen combination with a window sash and frame, a hold-fast plate 70 comprising members secured to the bottom edge of said sash and having portions bent downwardly to provide longitudinally extending vertical flanges disposed centrally with respect to said window sash, said 75 flanges opposing each other, and together being the same width as the bottom rail of said window sash and being secured thereto, a screen having its upper end positioned between said flanges, rivets extending through 80 said flanges and screen for securing the screen to the plate whereby the screen is coupled to the sash when the plate members are secured thereto, the said screen having its lower end connected to a spring roller 85 and the said roller being disposed within a longitudinal housing in a window sill and being adapted to wind and unwind from the roller when the sash is vertically moved.

In testimony whereof I affix my signature 90 in the presence of two witnesses.

TEOFIL GRZYWIENSKI.
